UNITED STATES PATENT OFFICE.

SAMUEL L. BURRISS, OF SOUTHPORT, NORTH CAROLINA.

CALIPERS.

1,199,155.

Specification of Letters Patent. Patented Sept. 26, 1916.

Application filed October 4, 1915. Serial No. 54,017.

To all whom it may concern:

Be it known that I, SAMUEL L. BURRISS, a citizen of the United States, residing at Southport, in the county of Brunswick and State of North Carolina, have invented certain new and useful Improvements in Calipers, of which the following is a specification, reference being had to the accompanying drawings.

10 This invention relates to certain improvements in calipers, and it is an object of the invention to provide a device of this general character which may be employed with convenience and facility in connection with interior or exterior measurements.

15 It is also an object of the invention to provide a novel and improved device of this general character wherein is included a scale whereby a single instrument may be employed for dual purposes.

20 The invention consists in the details of construction and in the combination and arrangement of the several parts of my improved caliper whereby certain important advantages are attained and the device is rendered simpler, less expensive and otherwise more convenient and advantageous for use, all as will be hereinafter more fully set forth.

25 30 The novel features of the invention will be carefully defined in the appended claim.

In order that my invention may be the better understood, I will now proceed to describe the same with reference to the accompanying drawings, wherein—

35 Figure 1 is a view in plan of a caliper constructed in accordance with an embodiment of my invention; and Fig. 2 is an enlarged sectional view taken substantially on the line 2—2 of Fig. 1.

40 As disclosed in the accompanying drawings, 1 denotes a flat body preferably of metal and having one margin straight, as at 2, and provided with the scale graduations 3 which may be in accordance with inches and fractions thereof or in accordance with the metric system. The opposite end of the body 1 is provided with the communicating depressions 4 adapted to receive the extremities of the legs 5, said extremities being substantially semi-circular in top plan with their peripheries beveled to engage the beveled walls 6 of the depres-

sions 4 and the body 1 has produced thereon around the wall 6 the scale graduations 7 for caliper readings and each of the legs has produced adjacent its curved end the thread line 8 serving as an index to coact with the adjacent graduation 7. The lines 8 are disposed at the same side of the pivots 9 of the legs 5 and it will therefore be perceived that the right leg will be employed for exterior caliper use while the left leg will be employed for interior caliper use. The pivots 9 are preferably spring rivets which permit sufficient play to allow one leg to overlap the other.

45 The adjacent peripheries of the curved ends of the legs 5 are provided with the intermeshing teeth 10 whereby the movement of one of the legs results in a simultaneous movement of the second leg and the same degree of movement.

50 The legs 5 are preferably reversely bowed and have their extremities provided with the outwardly disposed pointed extensions 11, each being arranged at the same angle relative to its coacting leg. At right angles to the extensions 11, the free ends of the legs 5 are provided with the heels 12 substantially rectangular in form, the corners of which serve as exterior and interior contact points. In practice, it is preferred that when the heels 12 are in contact that five teeth be disposed above the bight of the curved ends of the legs and three below. This gives the limit of measuring capacity of the device. It is also necessary in order that when one leg passes the other so as to remove the instrument when used for interior work, that the teeth still be in contact and the effective operation of the instrument be maintained.

55 60 From the foregoing description, it is thought to be obvious that a caliper constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as 65 70 75 80 85 90 95 100 105 limiting myself to the precise arrangement

and formation of the several parts herein shown in carrying out my invention in practice.

I claim:

- 5 A caliper comprising a flat body, legs pivotally engaged with said body, adjacent portions of said legs being in mesh whereby the same are caused to rotate simultaneously, the free extremities of the legs being provided with pointed extensions and with 10 heels, the pivoted extremities of the legs be-

ing arcuate, each of said arcuate extremities being provided with an index, said body being provided with graduations coacting with the indexes on the legs.

In testimony whereof I hereunto affix my signature in the presence of two witnesses.

SAMUEL L. BURRISS.
